UNITED STATES PATENT OFFICE

JOHN L. HARRIS, OF THOMSON, NEW YORK

HYDRAULIC FELT CONDITIONER OR THE LIKE

Application filed May 14, 1930. Serial No. 452,477.

This invention relates to improvements in hydraulic paper making machines generally, and has for its main object to provide a type thereof which operates in a highly effective and efficient manner to clean felted stock while the paper felting machine is in operation.

Another object of the invention is the provision of a paper making machine having means for cleaning the felt while permitting the proper formation of and the knitting together of the fibre so that water will pass freely through the felt when said felt enters the press rolls.

15 A further object of the invention is to provide an apparatus of the class set forth which is capable of efficient operation and with equal facility from either hydraulic pressure applied to the same from the usual mill service water supply or air pressure from a special compressed air supply.

With the foregoing and other equally important objects and advantages in view, the invention resides in the certain new and useful combination, construction and arrangement of parts as will be hereinafter more fully described, set forth in the appended claims, and illustrated in the accompanying drawings, in which:

30 Figure 1 is a fragmentary side elevation of a conventional form of bed or table of a paper felting machine, and showing a practical embodiment of the improved conditioning or cleaning apparatus in operative assembly therewith;

Figure 2 is an enlarged fragmentary view similar to that of Figure 1;

Figure 3 is an enlarged vertical transverse section, taken on the line 3—3 of Figure 2;

40 Figure 4 is a slightly enlarged fragmentary vertical longitudinal section through the power cylinder and piston; and

Figure 5 is an enlarged fragmentary horizontal section, taken on the line 5—5 of Figure 2.

Referring to the drawings, wherein like characters of reference designate corresponding parts in the several views thereof, the embodiment of the invention as shown therein by way of example only, is constituted in

oppositely arranged supports or legs 10 on the upper ends of which a body or frame 11 is suitably secured, as by means of the cap screws or the like 12.

This body or frame 11 is preferably of elongated tubular form, being made up from a suitable length of pipe stock of a proper diameter if desired, and is longitudinally slotted, as at 13, at its opposite sides to receive rollers 14 therein. These rollers 14 are journaled on pipe extensions 15 and 15' leading from the opposite outlets of a side outlet T form of pipe coupling 16, which has its upper outlet 16' engaged by the lower end of an arm 17 depending from a piston rod 18 disposed above and extending parallel to the frame member 11. This arm 17 is engaged through a longitudinal slotway 19 formed in the top side of the frame member 11.

A pipe extension 15 is angularly coupled at its outer end to one end of a pipe section 20 which has its other end angularly coupled, as at 21, to a second pipe section passed transversely through the side slotways 13 in the frame member 11. Journaled on the transverse pipe sections aforesaid are a pair of rollers 14' which likewise engage in the side slotways 13.

The free ends of the pipe extensions 15' and the transverse pipe section aforesaid are each provided with a downwardly angled L-coupling 22 from which a relatively short pipe section 23 depends and supports a spray head 24 on its lower end.

The rod 18 has the depending arm 17 secured to the same immediately adjacent an end thereof and has its other end extending inwardly of a packing gland 25 at the inner end of a cylinder 26 which is mounted in brackets 27 secured as by means of the cap screws or the like 27', on the upper side of the frame member 11.

The end of the rod 18 projected into the cylinder 26 carries a piston consisting of metal end plates or washers 28 spaced apart to clamp cupped leather washers or the like 29 between the same and an intermediate metal washer 30; the plates or washers 28 being abutted at their outer sides by clamp nuts 31 screw threaded on the rod 18.

The opposite ends of the cylinder 26 are connected by pipe assemblies 32 and 32' to ports 33 and 33' respectively which are formed in a valve body 34 bolted, as at 35, to an arm 36 offset inwardly from the supporting bracket 27 at the outer end of the cylinder 26. These ports 33 and 33' open outwardly of the opposite vertical sides of a valve body 34 and are angled interiorly 10 thereof in a forward direction where they open into a passageway 37 extending horizontally through the valve body in a plane parallel to that of the cylinder 26.

A sliding valve 38 is mounted in the passageway 37 and has oppositely directed stem portions 39 and 39' projecting outwardly of the opposite ends of the passageway through enlarged bore portions 37' and 37'' and through packing glands 40 screw threaded 20 into the latter. The valve 38 is of elongated form and has enlargements 38' and 38'' at its opposite ends, which move to centered position with respect to the ports 33 and 33' corresponding with the reverse directional 25 movements of the valve 38 as will be herein-after more fully explained.

Opening into the front side of the valve body 34 and into the passageway 37, at a point substantially mid-way between the 30 ports 33 and 33' is an air or water inlet 41, while an outlet 42 leads outwardly of the same side of the valve body but from the enlargement 37' of the passageway 37. An exhaust port 43 extends through the outer 35 part of the valve body 34 in parallel relation to the passageway 37 therein and connects the enlarged bore portions 37' and 37'' in order to exhaust the air or water from the inlet side of the valve body to the outlet side thereof substantially as is shown in Figure 5.

The free end of the valve stem or rod 39 is pivotally connected, as at 44, to one end of a pair of oppositely disposed links 45 which 45 have their outer ends pivoted, as at 46, to a roller 46' engaged in an arcuate slot 47 formed in an actuating arm 48; the latter being pivoted, as at 49, at an intermediate point, below the slot 47, to an offset portion 50' formed at the upper end of the adjacent 50 of the vertical supports or legs 10.

The lower end of the arm 48, in turn, is pivoted as at 50, to a block 51 mounted on the 55 free end portion of a pitman or rod 52 between a pair of spacer sleeves 50' which have their outer ends abutted against collars 52' secured to the pitman or rod 52 by means of pins 52''. Formed on the arm 48, below the slot 47, is a second arcuate slot 53 into which a stop member or pin 54 projects from its point of securement in the bracket arm 36, in order to limit the opposite swinging movements of the arm 48 and consequently the length of travel of the valve 38 in the passageway 37 of the valve body 34.

The other or inner end of the pitman or rod 52 is secured in the lower end of an arm 55 dependent from the pipe section 20 which is slidably relative thereto along with the spray nozzles 24, when the piston rod 18 is actuated by the alternate admission and exhaust of water or air to and from the opposite ends of the cylinder 26.

In order to assist the rocking or oscillating movement of the arm 48 under the reciprocating action of the pitman or rod 52, the upper end thereof is formed to provide an extended portion 48' on which a weight 55 is adjustably secured by means of a set screw or the like 56.

In the operation of the apparatus, as thus constructed and arranged and positioned over the felt bed or table *a* of a paper felt-ing machine, the inlet pipe 41 will be connected to a suitable source of water or air supply and the outlet pipe 42 to a waste drain or the like, while a flexible hose connection 57 will lead to the side outlet 16' of the T-coupling 16 from a hot water supply for the distribution of the water to the spray nozzles 24.

With the sliding valve 38 in the position as shown in Figure 5 and the sprayer head structure and the piston rod 18 at the left hand end of the frame 11, pressure from the inlet 41 will pass to the inlet port 33, through the passageway 37 and from thence by way of the pipe assembly 32' to the left hand end of the cylinder 26, when the piston in the latter will be moved with the rod 18 toward the 100 rod. During the final movement of the piston and rod assembly 18 in this right hand direction, the shoulder 58, at the outer connected angled end of the pipe extension 21 will be forced against the arm 53 which 105 will then move therewith during the remainder of its travel.

This movement of the arm 53 is transmitted by the pitman or rod 52 to the pivot block 51 and pivot 50, when the arm 48 will be swung on the pivot 49 to a left hand position, the weight 55 acting to accelerate such movement after the arm passes the vertical center of its arc of travel.

This movement of the arm 48 is transmitted to the valve 38 by the links 45 when the valve takes position in the passageway 37 of the valve 36 to establish communication between the inlet 41 and the port 33. Here, water or air will pass the passageway 37 from the inlet 41 and will pass into the port 33 to and through the pipe assembly 32 to the right hand end of the cylinder 26, when the piston and rod assembly 18 together with the spray head structure, will move to the left. With the left hand movement of the piston, the water or air in the cylinder 26, at the opposite side of the piston, will be forced back through the pipe assembly 32' to and through the port 33' and into the pas-

sageway 37, from hence, it will pass through the exhaust port 43 and outwardly of the outlet 42.

As soon as the sprayer head assembly has nearly traversed the frame 11 in the left hand direction of its travel, the shoulder 58' at the outer angled end of the pipe extension 15 strikes the arm 53 and moves the same with it to the limit of its travel, when the pitman or rod 52 will cause the arm 48 to again swing on its pivot but in a right hand direction to bring the valve 38 back to its first position as aforesaid.

By this arrangement, the sprayer head with the nozzles 24 will be passed over the paper machine felt at a very slow speed to effect a thorough washing off or cleaning of the felt stock in a desired manner. By providing two spray nozzles 34 as shown due allowance is made for full coverage of the felt.

Without further description, it is thought that the features and advantages of the invention will be readily apparent to those skilled in the art, and it will of course be understood that changes in the form, proportion and minor details of construction may be restored to, without departing from the spirit of the invention or its scope as claimed.

I claim:

1. In an apparatus of the class described, a frame comprising a cylindrical support having longitudinal slots at the opposite sides thereof, an inlet pipe within the support, a T connected to the opposite ends of the inlet pipe and having branch pipes extending through the slots in the support, the free ends of the branch pipes being provided with nozzles, flanged rollers received within the slots and supporting the branch pipes and the inlet pipe for movement longitudinally of the support, and means for causing reciprocating movement of the inlet pipe in the support.

2. In an apparatus of the class described, a frame comprising a cylindrical support having longitudinal slots at the opposite sides thereof, an inlet pipe within the support, a T connected to the opposite ends of the inlet pipe and having branch pipes extending through the slots in the support, the free ends of the branch pipes being provided with nozzles, flanged rollers received within the slots and supporting the branch pipes and the inlet pipe for movement longitudinally of the support, hydraulic means for causing reciprocation of the inlet pipe within the support.

3. In an apparatus of the class described, a frame comprising a cylindrical support having longitudinal slots at the opposite sides thereof, an inlet pipe within the support, a T connected to the opposite ends of the inlet pipe and having branch pipes extending through the slots in the support, the free ends of the branch pipes being provided

with nozzles, flanged rollers received within the slots and supporting the branch pipes and the inlet pipe for movement longitudinally of the support, means for causing reciprocating movement of the inlet pipe in the support, an oscillating means for causing reversal of the movement of the inlet pipe when the pipe reaches its limits of movements at the opposite ends of the frame.

4. In an apparatus of the class described, a frame comprising a cylindrical support having longitudinal slots at the opposite sides thereof, an inlet pipe within the support, a T connected to the opposite ends of the inlet pipe and having branch pipes extending through the slots in the support, the free ends of the branch pipes being provided with nozzles, flanged rollers received within the slots and supporting the branch pipes and the inlet pipe for movement longitudinally of the support, hydraulic means for causing reciprocation of the inlet pipe within the support, a valve for controlling the flow of hydraulic fluid to the hydraulic means, and an oscillating means for operating the valve to cause a reversal of flow of the hydraulic means for causing a reverse movement of the reciprocating means when the inlet pipe reaches the limit of its movements at the opposite ends of the frame.

5. In an apparatus of the class described, a frame comprising a cylindrical support having longitudinal slots at the opposite sides thereof, an inlet pipe within the support, a T connected to the opposite ends of the inlet pipe and having branch pipes extending through the slots in the support, the free ends of the branch pipes being provided with nozzles, flanged rollers received within the slots and supporting the branch pipes and the inlet pipe for movement longitudinally of the support, hydraulic means for causing reciprocation of the inlet pipe within the support, a valve for controlling the flow of hydraulic fluid to the hydraulic means, an oscillating means for operating the valve to cause a reversal of flow of the hydraulic means for causing a reverse movement of the reciprocating means when the inlet pipe reaches the limit of its movements at the opposite ends of the frames, and means on one of the branch pipes for engagement with the oscillating means for actuating said oscillating means.
